SWIVEL VALVE

Application filed March 12, 1929. Serial No. 346,377.

This invention relates, generally, to improvements in radiator valves; and the invention has reference, more particularly, to an improved radiator valve which is not only manually operable to regulate the supply of heating fluid furnished to a radiator, but which is constructed so as to permit turning movement of the radiator relative to the source of heat supply, whereby thorough cleansing, painting, etc., of the radiator and adjacent room surfaces is made possible.

Heretofore when it was desired to have a radiator turnable with respect to its supply pipe, it has been the practice to employ a hole low steam packed pivot joint attached to the supply pipe to permit the turning movement of the radiator, and to obtain heat regulation, a radiator control valve was inserted between such joint and the radiator. Such arrangement of pivot joint and radiator valve in series necessitates the placing of the radiator at an objectionably large distance from the supply pipe and at the same time results in the radiator having an unattractive appearance.

It is the principal object of the present invention to provide a novel swivel valve which not only serves to regulate the supply of the heating fluid to the radiator, but which is constructed so as to enable turning movement of the radiator with respect to its supply pipe.

Also, the novel swivel valve of this invention provides an attractive, unitary and compact structure, which is very similar in appearance to the ordinary radiator valve, but which is nevertheless adapted to permit turning movement of the radiator with respect to its supply pipe.

Other objects of this invention, not at this time more particularly enumerated, will be clearly understood from the following detailed description of the same.

The invention is clearly illustrated in the accompanying drawings, in which:

Fig. 1 is a view in front elevation of a movable radiator equipped with the novel swivel valve of this invention;

Fig. 2 is a view taken along line 2-2 of Fig. 1 but illustrating the radiator swung

outwardly from its normal position adjacent a wall;

Fig. 3 is a vertical sectional view of the novel swivel valve of this invention;

Fig. 4 is a plan view with parts broken away of the valve shown in Fig. 3;

Fig. 5 is a plan view of a washer with integral key employed in the valve of this invention;

Fig. 6 is a plan view of a helical spring also employed in the valve of this invention.

Similar characters of reference are employed in all of the hereinabove described views, to indicate corresponding parts.

Referring now to the several figures of the drawings, the reference character 1 designates a radiator normally positioned adjacent and in substantially parallel relation to a wall 2. Radiator 1 is adapted to be swung outwardly about the stationary steam or hot water supply pipe 3 as an axis. Radiator 1 is preferably provided with rollers 4 and 5 to enable the easy movement of this radiator over the floor 6. Two such rollers 4 are used to support the free end of the radiator, while a single roller 5 is preferably used to support the end of the radiator adjacent the pipe 3.

The bearing brackets 7 for rollers 4 are provided with upturned fingers 8 which are adapted to be pressed into frictional engagement with the feet 9 of the radiator 1. The bearing bracket 11 for roller 5 is adapted to extend between two of the feet 9 of the radiator, and this bearing bracket also has upwardly extending fingers 12 for frictionally engaging the feet 9. The construction of the bearing brackets 7 and 11 enables the ready mounting of rollers 4 and 5 on the feet of any radiator, since these bearing brackets and rollers are secured to the feet 9 by merely mounting the bearing brackets on the bottoms of the feet and pressing the retaining fingers against the sides of such feet.

The peculiar construction of the novel swivel valve 13 permits the turning of the radiator 1 with respect to pipe 3. Valve 13 comprises a hollow substantially cylindrical valve body 14. The internal diameter of this valve body is reduced at its lower por-

tion forming an inlet opening 10 that is threaded for the greater portion of its length for reception of the supply pipe 3. The lower exterior portion of valve body 14 is provided with a hex-head 15 that is utilized in threading the valve body 14 on or off of the upper end of pipe 3. Valve body 14 is also internally threaded at its upper end portion for the reception of valve cap 16.

10 Valve cap 16 is formed with a square head 17 to enable the ready threading of this cap upon the valve body 14. Valve cap 16 is provided with an annular flange 18 that is adapted to abut the upper edge of the valve body 15 in overlying relation, thereby forming a fluid tight joint between the cap 16 and the valve body 14. Valve cap 16 is provided with a central, vertically extending aperture 19, that is threaded for the greater part of its length 20 at 26 to receive the threaded central portion 20 of the valve stem 21. Valve stem 21 projects upwardly from the valve cap 16 and has a circular handle 22 secured to its upper end as by a screw 23. A stuffing box 24 is threaded upon the top of valve cap 16 and contains packing material 25 for sealing the joint between the valve stem and valve cap. The lower end of valve stem 21 carries a disk valve 27 that cooperates with an annular valve seat 28 formed in the valve body 14 adjoining the inlet opening 10. By manipulating the handle 22, the disk valve 27 may be operated to either open or close the inlet opening 10.

25 The exterior surface of the valve body 14 is upwardly and inwardly tapered and is formed so as to provide two outer inclined bearing surfaces 30 and 31. Bearing surface 30 is provided near the top of the valve body 14, while bearing surface 31 is provided near the bottom of this member. These two bearing surfaces are adapted to cooperate with corresponding inclined bearing surfaces 33 and 34 formed on the interior of a casing 32. These cooperating bearing surfaces are nicely matched as by lapping so as to form extremely snug fits while at the same time offering little resistance to turning movement of the casing with respect to the valve body. Owing to the snug fit of these cooperating bearing surfaces, there is no possibility of fluid within casing 32 escaping between these surfaces to the exterior of the valve 13.

30 That portion of the valve body 14 that extends between bearing surfaces 30 and 31 has its outer surface slightly recessed and is provided with radially extending apertures 35 connecting the interior of the valve body with an annular recess 36 provided in the casing 32. The annular recess 36 is connected to an outlet opening 38 provided in a laterally extending member 39 of the casing 32. Outlet member 39 is connected by a union pipe joint 40 to the intake pipe 41 of the radiator 1.

35 The upper end of casing 32 carries a fibre

washer 44, which surrounds the valve body 14. A metallic washer 42 having an integral inwardly projecting key 46 (see Fig. 4) is mounted upon fibre washer 44. Key 46 is vertically movable in a key way 47 formed in the upper end portion of valve body 14. A flat helical compression spring 43, preferably of two turns, is mounted on the top of metallic washer 42. An internally threaded ring 45 is threaded upon the upper end of the valve body 14 and is adapted to bear against the spring 43. This ring is adapted to be adjusted as by a spanner wrench to thereby vary the bearing pressure existing between the cooperating bearing surfaces 30, 33 and 31, 34. 70 The pressure of ring 45 is exerted through spring 43, metallic washer 42 and fibre washer 44 to the casing 32, thereby urging the bearing surfaces 33 and 34 of this casing into intimate contact with bearing surfaces 30 and 31. 75 The tension of spring 43 as varied by ring 45 determines the desired continuous pressure to be exerted between these cooperating bearing surfaces. 80

85 In operation, by adjusting handle 22, the flow of heating fluid to the radiator 1 is controlled. Owing to the construction of valve 13 the radiator may readily be turned about its supply pipe 3. While the radiator is being thus turned, the casing 32 turns about the stationary valve body 14 and the bearing surfaces 33 and 34 turn upon bearing surfaces 30 and 31 respectively. The fibre washer 44 may turn somewhat with the casing, but the metallic washer 42 being keyed to the valve body does not turn so there is no tendency to turn the spring 43 or the ring 45, and hence there is no tendency to loosen the latter ring and relieve the pressure on the cooperating bearing surfaces 30, 33 and 31, 34. 90 The snug fit and peculiar construction of these bearing surfaces eliminates the necessity of packing between these joints and the exterior of the swivel valve. 95

100 While I have described my novel swivel valve as arranged for use in connection with radiators, to render the same movable as explained, it will be obvious that the novel valve may be also used in connection with any other apparatus or device which is desired to be rendered movable about the axis of a fixed supply pipe. 110

115 As many changes could be made in the above construction and many apparently widely different embodiments of this invention could be made without departing from the scope thereof, it is intended that all matter contained in the above description or shown in the accompanying drawings shall be interpreted as illustrative and not in a 120 limiting sense. 125

What is claimed is:—

1. In combination with a radiator and a supply pipe therefor, a swivel valve for regulating the supply of heating fluid to said 120

5 radiator and constructed so as to enable said radiator to be turned with respect to said supply pipe, said swivel valve comprising a stationary valve body connected to said supply pipe, and a movable casing surrounding said valve body and connected to said radiator, said valve body serving to conduct fluid from said supply pipe to said casing.

2. In combination with a radiator and a supply pipe therefor, a swivel valve for regulating the supply of heating fluid to said radiator and constructed so as to enable said radiator to be turned with respect to said supply pipe, said swivel valve comprising a stationary valve body connected to said supply pipe, and a movable casing surrounding said valve body and connected to said radiator, said valve body serving to conduct fluid from said supply pipe to said casing, and 20 means within said valve body for controlling the flow of heating fluid therethrough.

3. In combination with a radiator and a supply pipe therefor, a swivel valve for regulating the supply of heating fluid to said radiator, said valve comprising, a stationary valve body connected to said supply pipe, bearing surfaces provided on said valve body, a movable casing surrounding said valve body, bearing surfaces provided on said casing and adapted to cooperate with the bearing surfaces of said valve body to enable the turning of said radiator with respect to said supply pipe, and means interposed between said valve body and said casing for regulating the pressure exerted between said cooperating bearing surfaces.

4. In combination with a radiator and a supply pipe therefor, a swivel valve comprising, a hollow substantially cylindrical valve body connected to said supply pipe, said valve body having exterior tapered bearing surfaces, a casing surrounding said valve body and connected to said radiator, said casing having internal inclined bearing surfaces cooperating with the bearing surfaces of said valve body to enable the turning of the casing and hence said radiator with respect to said valve body and said supply pipe.

5. In combination with a radiator and a supply pipe therefor, a swivel valve comprising, a hollow substantially cylindrical valve body connected to said supply pipe, said valve body having exterior tapered bearing surfaces, a casing surrounding said valve body and connected to said radiator, said casing having internal inclined bearing surfaces cooperating with the bearing surfaces of said valve body to enable the turning of the casing and hence said radiator with respect to said valve body and said supply pipe, said valve body serving to conduct heating fluid from said supply pipe to said casing for delivery to said radiator and a disk valve 65 contained within said valve body and adjust-

able for regulating the supply of heating fluid from said supply pipe.

6. In combination with a radiator and a supply pipe therefor, a swivel valve comprising, a hollow substantially cylindrical valve body connected to said supply pipe, said valve body having exterior tapered bearing surfaces, a casing surrounding said valve body and connected to said radiator, said casing having internal inclined bearing surfaces cooperating with the bearing surfaces of said valve body to enable the turning of the casing and hence said radiator with respect to said valve body and said supply pipe, resilient means interposed between said valve body and said casing for exerting a desired pressure between said cooperating bearing surfaces, and means for regulating the tension of said resilient means, said valve body serving to conduct heating fluid from said supply pipe to said casing for delivery to said radiator and a disk valve contained within said valve body and adjustable for regulating the supply of heating fluid from said supply pipe.

7. In combination with a supply pipe and a relatively movable outlet pipe, a substantially cylindrical valve body connected to said supply pipe, external tapered bearings provided on said valve body, a valve casing encircling said valve body and provided with an internal passage communicating with said outlet pipe, tapered internal bearings provided on said casing for cooperating with said external bearings, said casing being relatively movable with respect to said valve body, said valve body having an internal passage communicating with said supply pipe and with said internal passage of said casing, spring means interposed between said valve body and casing for maintaining a predetermined pressure between said external and internal bearings, and a member non-rotatably connected to said valve body and interposed between said spring means and said casing for eliminating frictional engagement between said casing and said spring means.

In testimony that I claim the invention set forth above I have hereunto set my hand this 18th day of Feb., 1929.
